CLOTH FOLDING AND MEASURING MACHINE.

Application filed November 8, 1920. Serial No. 422,677.

To all whom it may concern:

Be it known that I, HERMAN D. BRENNER, a citizen of the United States, of Chicago, Cook County, Illinois, have invented a certain new and useful Improvement in Cloth Folding and Measuring Machines, of which the following is a specification.

This invention relates to machines for folding and measuring cloth, such as those employed in merchant tailoring establishments, or in other places where cloth must be folded or measured, or both, so that either folding or measuring by hand is not necessary.

Generally stated, the object of the invention is to provide an improved construction and arrangement whereby the cloth is properly folded, and is measured accurately, while traveling through the machine.

Another object is to provide an improved construction and arrangement whereby, in either a folding or a measuring machine, or in a machine for both purposes, the cloth is delivered smoothly to the machine, as by feeding it from a bolt or roll, and whereby any tension of the cloth is reduced and practically eliminated before the cloth reaches the folding means, or before it reaches the measuring means, so that better results are ensured in the folding of the cloth, or in the measuring thereof, or both, depending upon the character and purpose of the machine in which the instrumentalities for thus feeding the cloth are employed.

A further object is to provide novel and improved folding means for ensuring a satisfactory folding of the cloth in the desired manner.

Another object is to provide a novel and improved arrangement of the measuring means, in conjunction with other elements, so that the cloth will be accurately measured as it travels through the machine.

It is also an object to provide certain features and details of construction and combinations tending to increase the general efficiency and the desirability of a machine of this particular character.

To these and other useful ends the invention consists in matters hereinafter set forth and claimed and shown in the accompanying drawings in which:

Figure 1 is a plan of a cloth folding and measuring machine embodying the principles of the invention, showing certain portions thereof broken away to shorten the view, and for convenience of illustration, 55

Figure 2 is a side elevation of the machine shown in Figure 1,

Figure 3 is an enlarged longitudinal section on line 3—3 in Figure 1, with certain central portions of the machine omitted or shown broken away for convenience in illustration,

Figure 4 is a transverse section on line 65 4—4 in Figure 1,

Figure 5 is an enlarged side elevation of the folding mechanism,

Figure 6 is a view similar to Figure 5, but showing said mechanism in a different 70 position.

As thus illustrated, the invention comprises a long table having a frame 1 and a flat table top 2, the length of said table depending upon conditions and requirements, as will hereafter more fully appear. 75 A feed roll 3 is suitable mounted in transverse position at the receiving end of the said table and a similar roll 4 is mounted at the discharge end of said table, while one or more intermediate rolls 5 are located at suitable points in the middle portion of the table. These rolls are all connected together by belts 6 of any suitable character in any suitable or desired manner, so that the rotary transversely arranged feed rolls thus provided rotate simultaneously with uniform speed in the same direction. It will be seen that these rolls extend a little above the top surface of the table; 80 so that the width of the cloth will be sustained by said rolls at intervals along the length of said table. Inclined brackets 7 are provided at the discharge end of the machine, and an idler feed roll 8 is provided 85 at its ends with journals or small hubs 9 that rest against the inclined sides of the brackets 7, so that this roll engages and exerts its weight against the positively driven feed roll 4 previously mentioned. The feed 90 roll 4 is driven by an electric motor 10 through the medium of a suitable gear connection 11, so that all of the feed rolls are driven simultaneously at the desired speed.

100

Guides 12 direct the cloth on to the roll 3, in the manner shown in Figure 3, and the cloth then moves forward toward the discharge end of the machine.

5 The folding mechanism comprises a swinging member 13 shaped somewhat like a hopper to receive the downwardly moving cloth 14, as shown in Figure 3, and the upper end of this member is pivoted at 15 10 on the frame of the machine. With this arrangement the swinging member or folder 13 swings back and forth upon a transverse axis, and in so doing folds the cloth back and forth on the floor in the manner indicated 15 in Figures 5 and 6. For the operation of the folder a sprocket chain 16 connects one end of the roll 14 with a rotary crank 17 suitably mounted on the frame of the machine, and this crank is connected by a pitman 18 with the said folder. With this arrangement, the electric motor 10 drives all of the feed rolls, and the feed roll 4 communicates power to the swinging folder 13, so that the power for operating the cloth 25 feeding and the cloth folding means is all derived from the same motor or other source.

The means for measuring the cloth may be of any suitable, known or approved character. Preferably, however, in accordance with the invention, means for this purpose are provided comprising a transversely arranged arm 19 which is hinged to one side of the body frame at 20, so that the cloth 14 30 will pass smoothly and readily below the said arm, and a cloth meter 21 of any suitable, known or approved character is mounted on the end of said arm and provided with a wheel 22 that rests upon the traveling 35 cloth, whereby said meter is operated by the feeding motion of the cloth as it travels through the machine. When desired, the cloth meter thus provided and operated can be swung upward into the position indicated 40 by the dotted lines in Figure 4, but in operation the wheel 22 rests upon the cloth, near the feed roll 4, in the manner shown.

Means of any suitable character can be provided for supplying the cloth to the receiving end of the machine. Preferably, however, such means include a pair of supporting rolls 23 arranged transversely of the direction of travel of the cloth, in the same horizontal plane, and mounted upon upright members 24 in position near the receiving end of the machine. The bolt or roll of cloth 25 is suspended from the feed rolls 23 in a loop of the cloth, as shown in Figure 3, so that the cloth as it unwinds extends around and over the rolls 23 and then downward under the roll or bolt of cloth and then upward and over one of the rolls 23 and finally to the roll 3, previously described.

65 With this construction and arrangement,

the cloth is delivered with little tension to the roll 3, as it requires little pull to draw the cloth from the bolt or roll 25, but because of the length of the table top 2 and the general arrangement of the feeding instrumentalities any tension of the cloth is considerably reduced, and eliminated, if possible, before it reaches the measuring means and the folding means. If the cloth were taken directly from the rolls 23 to the roll 4, or even to a point substantially under the measuring means, the short distance thus traveled by the cloth would result in some tension, and neither the folding nor the measuring would be of the desired character; but, by reason of the comparatively long and loose stretch of practically floating cloth provided between the first feed roll 3 and the final feed roll 4 any tension of the cloth is pretty much confined to the portion 70 which is traveling from the rolls 23 to the roll 3, and any tension completely disappears, or practically so, while the cloth is then traveling horizontally on the table, so that better results are ensured in the measuring and folding of the cloth. The tension of the cloth as it leaves the bolt or roll 25, or the resistance offered to the pulling of the cloth forward by the first feed roll 2, can be adjusted or regulated in any suitable or 75 desired manner, and such tension will depend largely on the character of the bearings of the rolls 23, as the less friction these bearings present the less resistance will be offered to the smooth and easily unwinding 80 of the cloth and the delivery thereof to the feed roll 3 of the receiving end of the machine. In practice ball bearings have been used for this purpose. This machine, of course, is for use after the cloth is sponged, and is especially adapted for feeding the cloth doubled over to form a double thickness, as this is desirable or necessary, as will be readily understood, in the further use of 85 the cloth for certain purposes. This machine is useful, for example, in the manufacture of clothing, in which case large quantities of cloth must be prepared for the cutters.

90 The surfaces of the different feed rolls can be sanded or otherwise rendered rough and adapted to feed the cloth without danger of slippage. With the long table and the feed rolls disposed at intervals, as explained, the cloth has time and opportunity to freely flatten out, so that wrinkles or creases are 95 eliminated as presented, and the cloth arrives in smooth and good condition at the point where it finally enters the folding means. The cloth practically floats along 100 in two superimposed thicknesses as stated, and its weight is sufficient to keep it flat 105 and in proper engagement with the feed rolls underneath the moving cloth.

110 The table 2, therefore, serves as a smooth- 115

ing and straightening means for the cloth, to straighten and smooth out wrinkles, creases and folds, means are provided for feeding the cloth to said smoothing means, 5 and folding means are arranged to pull and receive the cloth from said smoothing means.

Thus it will be seen that the long table over which the cloth passes is provided with positively driven feeding means at opposite 10 ends thereof, the positively driven drum or feeding roll 3 being interposed between the table and the means for supplying the cloth, whereby the cloth travels from the roll 23 to the drum 3 under some degree of pull or 15 tension, and then travels from the roll 3 to the roll 4 while practically under no tension or stretch whatever.

What I claim as my invention is:

1. In a cloth-measuring machine, means to 20 provide a horizontal surface for the cloth, instrumentalities for engaging the cloth at intervals in the length thereof and thereby feeding the cloth by carrying it along without tension over said surface, and a cloth 25 meter arranged to rest upon the cloth traveling on said surface.

2. A structure as specified in claim 1, said means being a long table with a flat top, and said instrumentalities comprising rolls 30 disposed at intervals in the length of said table, together with means for positively driving said rolls in unison at the same speed.

3. A structure as specified in claim 1, comprising a table with a flat top forming said surface, means subject to the pull of said instrumentalities to deliver the cloth to the receiving end of said table, and means from- 40 ing part of said instrumentalities to reduce the tension of the cloth before it passes under said cloth meter.

4. A structure as specified in claim 1, said instrumentalities comprising rolls over 45 which the cloth travels, an idler engaging one roll, and means for driving this one roll and thereby the other rolls, so that said rolls all rotate in unison at the same speed, said cloth meter being near said one roll.

5. A structure as specified in claim 1, said 50 instrumentalities comprising a driven feed roll, an idler roll engaging said feed roll, thereby to feed the cloth over and downward from the driven roll, in combination with a swinging folder in the form of a pendu- 55 lum member which allows the cloth to hang straight down and which is disposed below said rolls, and means whereby said driven roll transmits power to operate said member back and forth to fold the cloth.

6. A structure as specified in claim 1, in 60 combination with a folder, and means whereby the folder is operated by power from said instrumentalities.

7. A structure as specified in claim 1, in 65 combination with means for delivering the

unmeasured cloth smoothly to said instrumentalities, and means for folding the measured cloth without tension.

8. A structure as specified in claim 1, in combination with means for folding the un- 70 measured cloth without tension.

9. A structure as specified in Claim 1, adapted by means of said instrumentalities to reduce any tension of the cloth before it 75 passes under said meter.

10. A structure as specified in claim 1, said means comprising a long table, and said instrumentalities comprising rolls disposed at intervals along the length of said table, so that each roll extends a little above said 80 surface, and means for driving said rolls in unison at the same speed.

11. In a cloth folding machine, the combination of a folder which allows the cloth in double thickness to hang down straight 85 therein, means to operate said folder, and instrumentalities designed to feed the cloth to said folder in double thickness, said instrumentalities comprising a long table having feed rolls disposed at intervals along 90 the length thereof, to carry and feed the cloth forward, adapted to reduce the tension of the cloth before it reaches the folder, and means for supplying the cloth under tension to the first roll at the receiving end 95 of said table.

12. In a cloth folding machine, the combination of a folder which allows the cloth in double thickness to hang down straight 100 therein, means to operate said folder, and instrumentalities designed to feed the cloth to said folder in double thickness, said folder comprising a swinging member which allows the two thicknesses to hang down 105 straight, and said means to operate the folder comprising a crank and pitman operated by said instrumentalities.

13. In a cloth folding machine, the combination of a folder which allows the cloth in double thickness to hang down straight 110 therein, means to operate said folder, and instrumentalities designed to feed the cloth to said folder in double thickness, in combi- 115 nation with means to deliver the cloth smoothly to the machine, said instrumentalities having provisions to reduce any tension before the cloth reaches said folder.

14. In a cloth folding machine, the combination of a folder which allows the cloth in double thickness to hang down straight 120 therein, means to operate said folder, and instrumentalities designed to feed the cloth to said folder in double thickness, said instrumentalities comprising positively driven 125 rolls disposed at intervals below the cloth, adapted to carry the cloth forward in double thickness in a horizontally disposed plane, with one of said rolls above said folder, and a loose idler engaging said one roll to help feed the cloth downward to said folder. 130

15. In a cloth folding machine, the combination of a folder which allows the cloth in double thickness to hang down straight therein, means to operate said folder, and 5 instrumentalities designed to feed the cloth to said folder in double thickness, in combination with rotary means for suspending a bolt or roll of cloth in position to feed the cloth to said instrumentalities, said rotary 10 means being adapted for insertion in a loop of the cloth, so that the bolt or roll hangs below said rotary means.

16. A structure as specified in claim 1, in combination with rotary means to suspend 15 a roll or bolt of cloth in a loop thereof to feed the cloth to said instrumentalities.

17. A structure as specified in claim 1, said cloth meter being hinged to float on the moving cloth near the discharge end of 20 the machine.

18. A structure as specified in claim 1, adapted especially by engagement with the cloth at intervals in the length thereof for feeding the cloth in double thickness without 25 stretching thereof.

19. In a cloth folding machine, the combination of a folder which allows the cloth in double thickness to hang down straight therein, means to operate said folder, and 30 instrumentalities designed to feed the cloth to said folder in double thickness, having means adapted especially for feeding the cloth at the same speed at intervals in the

length thereof and folding the cloth in double thickness without wrinkles or tension. 35

20. In a machine for measuring and folding cloth, the combination of feeding means, means to supply the cloth to said feeding means, smoothing and straightening means 40 to receive and feed the cloth from said feeding means, folding means to receive the cloth from said smoothing means, and measuring means to measure the cloth passing through the machine. 45

21. A structure as specified in claim 20, said smoothing means comprising a horizontally disposed table with means at each end thereof to cause the cloth to travel along the upper surface thereof, and said feeding means and said folding means being adapted 50 to feed and fold the cloth in double thickness.

22. In a machine of the class described, the combination of means for supplying sheet material, a horizontally disposed feeding table at one end of which the sheet material is delivered and from the other end of which the sheet material is discharged, 55 means at each end of said table for positively feeding the sheet material, thereby to reduce the tension or strain in the sheet material traveling over the table, and means 60 for operating said feeding means in unison.

HERMAN D. BRENNER.
